JIG GRINDER

Frederick C. Victory, Milford, Conn., assignor to
Moore Special Tool Co., Inc., Bridgeport, Conn.

Application July 28, 1950, Serial No. 11,455

Term of patent 14 years

(Cl. D37—1)

To all whom it may concern:

Be it known that I, Frederick C. Victory, a citizen of the United States, residing at Milford, in the county of New Haven, and State of Connecticut, have invented a new, original, and ornamental design for Jig Grinder of which the following is a specification, reference being had to the accompanying drawings forming a part hereof.

Fig. 1 is a perspective view taken from the front and one side of a jig grinder embodying my new design; and

Fig. 2 is a perspective view taken from the front and the other side thereof.

The back, not shown, is straight up to the head

portion, which head portion has its rear surface in a plane spaced slightly rearwardly of the rear surface of the major portion of the back and the entire back is substantially plain.

I claim:

The ornamental design for a jig grinder, substantially as shown and described.

FREDERICK C. VICTORY.
